FORMING ROUNDED EDGES ON BLADE-LIKE ELEMENTS

Samuel James Stabenell, Bristol, England, assignor to The Bristol Aeroplane Company Limited, Bristol, England, a British company

Application May 1, 1953, Serial No. 352,507

Claims priority, application Great Britain May 5, 1952

10 Claims. (Cl. 51—144)

This invention concerns a method and apparatus for forming rounded edges on blade-like elements by working on the elements with abrasive bands, belts or the like and relates more particularly to polishing the leading and trailing edges of a turbine or compressor blade. It is to be understood, however, that the invention may be applied to rounding the edges of flat as well as transversely curved blade-like elements, of which turbine and compressor blades are examples.

An object of the present invention is to provide a method and apparatus for producing a pair of rounded edges on a blade-like element at the same time.

Another object of the present invention is to provide a method and apparatus for rounding the edges of a blade-like element in which the shape of the edges may be accurately determined.

Another object of the present invention is to provide a method and apparatus for rounding the edges of a blade-like element rapidly and cheaply and, if necessary, by mass-production methods.

According to the present invention a method of abrading the long edges of a blade-like element to round them comprises inserting the element lengthwise between a pair of taut unsupported lengths of flexible abrading band, belt or the like, arranged with their abrading surfaces facing one another substantially parallel and spaced apart by less than the minimum width of the element, and then rotating the element substantially about its long axis.

According to a feature of the present invention said blade-like element may be inserted between said lengths while they are held spaced apart by more than the overall thickness of the blade-like element.

In the case of a flat, blade-like element the overall thickness is the true thickness of the element and in the case of a transversely curved element the overall thickness is the maximum distance from the convex surface to a line joining the long edges.

According to another feature of the present invention said lengths may be inserted between lengths which are portions of a single endless abrading band, or of a pair of endless abrading bands, and wherein said band or bands are driven to move said lengths across the long edges of the blade-like element while it is rotated. In this way a more rapid abrading action is obtained. While two separate bands, belts or the like may be used it is preferred that there is a single endless band or belt, two unsupported lengths of which are arranged as set forth above.

It is also preferred that the blade-like element be rotated first in one direction and then in the opposite direction since it has been found that with the element rotating in one direction only there is a tendency to form a non-symmetrical radius at the edges being rounded. Preferably also, the width of said band or bands, belts, or the like is less than the length of the blade-like element and the element is reciprocated substantially lengthwise while it is rotated.

According to another feature of the present invention apparatus for rounding the long edges of a blade-like

2

element may comprise a system of pulleys to support an endless flexible abrading belt, band or the like so that a pair of unsupported lengths of the belt are drawn taut, have their abrading surfaces substantially parallel and facing one another and spaced apart by less than the minimum width of the blade-like element to be rounded a work holder mounted to rotate about an axis of rotation extending between said lengths of the belt and adapted to support a blade-like element extending lengthwise along said axis of rotation with its long edges lying one on either side of said axis of rotation, and means to rotate said holder. Since the space between the unsupported lengths of the abrading band, belt or the like is less than the minimum width of the element, rotation of the latter will result in the unsupported lengths being displaced transversely so that the abrading band or belt is resiliently applied to the long edges of the element to round them.

It is preferred that, for automatic working of the apparatus, said lengths are spaced apart by more than the overall thickness of the blade-like element.

Preferably each of the unsupported lengths of the band, belt or the like passes at one end over a jockey pulley which is spring urged against the belt to taunt the belt, and said jockey pulleys are adjustable mutually to incline their axes whereby the abrading surfaces of said lengths converge transversely thereof so as more easily to accommodate a tapering blade-like element, so that the blade-like element can be inserted between the lengths of band, belt or the like without first parting the bands.

In the preferred apparatus means is provided to drive said endless band and the work holder is rotated successively in opposite direction and means is provided to reciprocate said work holder substantially along said axis of rotation, thereby to reciprocate a blade-like element mounted in said work holder substantially lengthwise as it is rotated, the element being rotated in one direction during the instroke of its reciprocating movement, and in the other direction during the outstroke of its reciprocating movement.

One method and apparatus in accordance with the present invention will now be described by way of example with reference to the accompanying drawings which show a machine for rounding the leading and trailing edges of turbine and compressor blades.

In the drawings:

Figure 1 is a front elevation of the machine, certain parts having been omitted for the sake of clarity,

Figure 2 is a side elevation to a smaller size of the machine shown in Figure 1,

Figure 3 is a partial somewhat diagrammatic view to a larger size in the direction of arrow 3 in Figure 2,

Figure 4 is a somewhat diagrammatic partial view in the direction of arrow 4 to a larger size in Figure 1, and

Figures 5 and 6 are cross-sectional views to a larger size showing the details of construction of parts of the machine shown in Figures 1 and 2.

Referring to Figures 1 and 2 of the drawings the machine comprises a base unit generally indicated at 10 within which is mounted an electric motor 11. The motor 11 drives two pulleys 12 and 13 one at each end of the motor drive shaft 14 and outside the base unit 10. Mounted on top of the base unit 10 at one end thereof is a bearing housing 15 for a shaft 17 of a pulley 16. The pulley 16 is positioned above the pulley 13, and the shaft 17 is eccentrically adjustable in the housing 15 to facilitate the fitting and removal of the belt which is later described. The shaft 17 is adjustable after loosening the knurled nut 18.

Mounted on the bearing housing 15 are two upwardly inclined arms 20, 21 (see Figure 1) forming a V. Both arms are slotted longitudinally as at 23, and are bridged

at their free ends by a horizontal strap 24 which has longitudinal slots 25 towards its ends. The arms 20, 21 are swingably mounted on the bearing housing each by means of a single bolt 30 so that each arm is angularly adjustable with respect to the vertical. A pulley wheel 26 is carried at the free end of each arm 20, 21 its shaft 27 passing through the slots 23 and 25 thereby fixing the strap 24 to the arms 20, 21. The slots 23 and 25 allow the arms 20, 21 and the pulleys 26 to be adjusted as desired.

A belt tensioning jockey unit 29 having a jockey pulley 31 is mounted in the slot 23 of each arm 20, 21 so that the pulleys 31 lie between the arms. Each pulley 31 is carried on a spindle 32 having a ball end 33 mounted in a spherical housing 34 formed in a two part block 35 carried at the end of an arm 36 hingeably connected at its other end by means of a bolt 37 to a plate 38 having a T-slot 39 (see Figure 3). The arm 36 carries a lever 40, and a coiled tension spring 41 is connected between the free end of the lever 40 and the plate 38 to urge the pulley 31 away from the arm on which it is carried. The units 29 are attached to their respective arm 20 or 21 by a bolt passing through the T-slot 39 in the unit and the slot 23 in the arm. In this manner the position of each pulley 31 is made adjustable.

An endless flexible felt belt 42, impregnated with abrasive material is positioned around the pulleys 13, 26 and 16 as shown in Figure 1. The run of the belt 42 follows a generally double V-shaped path, and the runs forming the inner V-shape pass over the jockey pulleys 31 which are positioned one above the other so that a pair of unsupported lengths 43 of the belt run substantially parallel with their abrading surfaces facing each other. The pulleys 31 being spring urged away from their respective arms tauten the belt, and the pulleys 31 and the arms 20, 21 may be adjusted to vary the space between the lengths 43.

Mounted on top of the base unit 10 at the opposite end to the bearing housing 15 is a timing gear unit 50. A pulley 51 (see Figure 2) is driven from the pulley 12 by means of a belt 52, and the pulley 51 drives a shaft 54 on which is mounted a worm gear 55 which in turn drives a worm wheel 56 mounted on a shaft 57 also carrying at one end, outside the casing of the unit 50, a slotted thrower or crank 58. On the opposite end of the shaft 57 is carried a finger 59 (see also Figure 4) which is arranged to engage a number of equally circumferentially spaced pins 60 mounted on a freely rotatable timing disc 61 to turn the disc. The disc 61 carries a cam 62 on its peripheral edge, and the cam 62 is arranged to engage a roller 63 carried at the end of an arm 64 in turn carried for swing movement by the casing of a "microswitch" 66 mounted on the top of the base unit 10. When the disc turns to bring the cam 62 against the roller 63, the arm 64 is moved, and opens the microswitch 66 which acts through a relay to stop the machine.

Fitted in the slot of the thrower 58 is a crank pin 70 which is adjustable along the slot to vary the throw of a rod 71 which is releasably and adjustably connected at its end remote from the pin 70, as later described, to a double arm 75 positioned generally vertically and having its lower end hinged between the limbs of a double arm 76 projecting horizontally from the base unit 10. The movement of the rod 71 is thereby imparted to the arm 75 which is made long compared with the length of the blade so that the free end of the arm reciprocates substantially horizontally to and fro.

Between the limbs of the arm 75 and towards its free end is adjustably mounted in elongated slots 82 a work-head having work-holder 80 which is rotatably driven from shaft 54 by means of a flexible drive 81.

The work-head contains an automatic reversing system for the work-holder 80. This will now be described.

Referring to Figure 5, the work-holder 80 is driven by a shaft 90 carrying two bevel gears 91 and 92. The

shaft 90 is axially slidable in the work-head to bring either the gear 91 or the gear 92 into driven engagement with a bevel gear 93 which is driven from the flexible drive 81. Pivoted to the work-head casing as at 94 is a lever 95. The lever passes through an aperture in the wall of the work-head casing and its inner end is forked to bridge the shaft 90 and engage in a circumferential groove 96 in the shaft whereby movement of the lever 95 shifts the shaft 90 axially to engage either the gear 91 or 92. The outer end of the lever 95 is restrained by a rod 98 (see Figure 2) connected thereto and also slidable in a block 99 carried on the strap 24 midway between its ends. The block 99 has a pair of screws 100 which are adjustable to vary the sliding friction of the rod 98 in the block 99. The arrangement is such that when the arm 75 is moving to the left in Figure 2 the lever 95 is held displaced to the right by the rod 98 which slides through the block 99, and the gear 92 is held in engagement with the gear 93 so that the work-holder 80 is rotated in one direction. When the arm 75 commences to move to the right in Figure 2, the lever 95 moves to the left relatively to the arm 75 so that the gear 92 is disengaged with the gear 93 and the gear 91 brought into engagement therewith. The work holder 80 then rotates in the opposite direction, and as the arm 75 continues to move to the right the rod 98 slides back through the block 99 and holds the lever 95 displaced to the left until the direction of movement of the arm 75 again changes.

It will be noted that the arm 75 reciprocates relatively slowly compared with the rotational speed of the work-holder 80, and that the work-holder rotates in opposite directions during successive strokes of its reciprocating movement. This ensures that the edges of the work piece are symmetrically rounded, there being a tendency to form a non-symmetrical radius if the work piece rotates always in the same direction.

As may be seen from Figure 5 a stop member 102 is pivoted to the top of the work head so that it is movable from an inoperative position (shown in full lines) in which the lever 95 is free to oscillate, to an inoperative position (shown in chain dotted lines) in which the lever 95 is held in a neutral position with both gears 91 and 92 disengaged with the gear 93. In this position of course the work holder remains stationary at least in the rotational sense.

As previously stated the rod 71 is releasably and adjustably connected to the arm 75. This is necessary in order that the position of the work head in relation to the belt 42 may be varied as required, and also in order that the arm 75 may be swung back for insertion and removal of the work piece from the holder. The connection between the rod 71 and the arm 75 will now be described. Referring to Figure 6, a split sleeve 106 is locked to the rod by means of a screw 107. Co-operating with the sleeve is a block 108. The block 108 is pivotally attached to one limb of the arm 75 by means of a pivot 109 (see also Figure 1), and is recessed so as to be a sliding fit over a reduced portion 110 of the sleeve 106, and the rod 71. A spring loaded plunger 111 is mounted on the block 108 and is arranged to pass through the block so that it is normally engaged in a circumferential slot 112 in the sleeve 106, thereby locking the sleeve in the block. When it is required to swing the arm 75 back to insert or remove a work piece the plunger 111 is lifted to free the block 108 from the sleeve 106 the block then being slid back along the rod 71 as the arm is moved. In order to adjust the distance of the work head from the belt 42 the screw 107 is loosened and the sleeve 106 moved to the desired position.

Metal guards 113 are provided over the belt 42 and the timing gear unit 50.

In carrying out the method using the machine just described, the blade whose long edges are to be rounded is mounted in the work holder 80 which is fitted with

a suitable chuck to take the blade, with its long axis substantially horizontal and directed between the lengths 43 of the belt 42. The length of the stroke of the rod 71 is then adjusted at the thrower 58 so that the whole length of the long edges of the blade will be reciprocated between the lengths 43, and the position of the blade in relation to the belt is adjusted by setting the sleeve 106 as previously described so that the blade will not be withdrawn from between the lengths 43. The arms 20, 21 and the jockey pulleys 31 are then adjusted so that the space between the lengths 43 is less than the minimum width of the blade, but greater than its overall thickness. This is preferred in automatic working since with the blade initially set with its width axis substantially vertical the blade can be moved freely to its position lying lengthwise between the lengths 43 of the belt without the necessity of having to part the lengths 43 to insert the blade. If the blade is a tapered blade the spindles 32 are mutually inclined, after slackening off the screws 115 (see Figure 2) to loosen the ball-end 33 of each spindle 32 in its housing 34, so that the lengths 43 of the belt converge transversely to correspond with the blade taper. The spindles 32 are set in their new positions by retightening the screws 115. It is to be understood that it is not an essential feature that the spindles 32 be mutually inclinable. The lengths 43 could have their abrading surfaces parallel before a tapered blade is inserted between them, the blade then twisting the belt transversely to incline the abrading surfaces to conform with the long edges of the blade.

Next, the timing disc 61 is set so that it has to make a complete revolution before the cam 62 operates the switch 66 and then the arm 75 is slid forward on the rod 71 and latched thereto so that the blade enters lengthwise between the length 43 of the belt. The motor 11 is then started, and the blade is rotated and reciprocated between the lengths 43 which are held taut and driven to pass over the long edges of the blade to round them. The operation automatically ceases when the disc 61 has been rotated by the finger 59 so that the cam 62 operates the switch 66 as previously described. The timing of the operation is dependent on the length of the finger 59 and the number of pins 60. These may be varied as desired. The felt belt is removed from time to time and impregnated with fresh abrasive material. The machine described is capable of rounding the long edges of turbine and compressor blades rapidly, cheaply, and with the necessary accuracy, and is therefore suitable in the mass production of such blades.

I claim:

1. Apparatus for rounding the leading and trailing edges of an aerofoil sectioned axial flow blade of the kind used in axial flow compressors and turbines, said apparatus comprising a base, a system of pulleys carried from said base, an endless abrading band of a width less than the length of a blade the leading and trailing edges of which are to be rounded, said band having an abrading surface and being supported by said pulley system with each of a pair of lengthwise portions of the band drawn taut between a pair of pulleys of said pulley system, said lengthwise portions being arranged substantially parallel with their abrading surfaces facing one another, and spaced apart by less than the minimum width of said blade a support means carried by said base, a work holder carried by said support means, means for rotating said work holder about an axis which passes between said lengthwise portions of the band, said work holder being adapted to support a blade, the leading and trailing edges of which are to be rounded, between said lengthwise portions of the band and lengthwise along said axis of rotation with the leading and trailing edges of the blade lying one on each side of said axis of rotation, means for moving said support means bodily to move said work holder repeatedly towards and away from said lengthwise portions of the endless band thereby to reciprocate a blade

carried in said work holder substantially in the direction of its length, and reversing means for reversing the direction of rotation of said work holder each time its direction of bodily movement is reversed.

5 2. Apparatus as claimed in claim 1 wherein said pulley system includes a pair of jockey pulleys and each of said lengthwise portions of the abrading band passes at one end over one of the jockey pulleys which is spring urged against the band to taunt the band, and said jockey pulleys are adjustable mutually to incline their axes whereby the abrading surfaces of said lengths converge transversely thereof so as more easily to accommodate a tapering blade.

10 15 3. Apparatus as claimed in claim 1 wherein said support means comprises an arm, and said work holder is carried towards one end of said arm which is hinged toward its other end to said base, and a rod, connected at one end to a crank carried for rotation from said base, is releasably and pivotally coupled to the arm to oscillate said arm to and fro about its hinge along a small arc thereby to move said work holder repeatedly towards and away from said lengthwise portions of the endless band.

15 20 25 4. Apparatus as claimed in claim 3 wherein said rod is releasably and pivotally coupled to said arm by means of a coupling comprising a sleeve on said rod, a block pivoted to said arm and recessed to receive said sleeve with the rod passing through said block, and a spring loaded plunger carried by said block to be received in a recess in said sleeve thereby to releasably lock said sleeve in said block.

20 25 30 5. Apparatus as claimed in claim 4 wherein said sleeve is adjustable along said rod to vary the position of said work holder in relation to said endless band.

35 40 45 6. Apparatus as claimed in claim 3 wherein said work holder is mounted on a work head carried by said arm, and said work holder rotating means comprises a work-holder driving shaft slidably journaled in said work-head, a pair of bevel gears mounted on said work holder driving shaft, a driven shaft journaled in said work head, a third bevel gear mounted on said driven shaft, said work holder driving shaft being slidably to engage either one of said pair of bevel gears with said third bevel gear, and said reversing means comprises a lever pivoted to said work head one end of said lever engaging said work holder driving shaft to shift the shaft axially when the lever is moved relatively to the work head, a friction device carried from said base, a rod slidable in said friction device, said rod being pivotally connected to the other end of said lever and restraining said lever to hold said pair of bevel gears alternately in driving engagement with said third gear during successive strokes of the oscillating movement of said arm, said lever being moved by said rod relatively to said arm when the direction of movement of said arm changes, to disengage one of said pair of bevel gears, and engage the other, and thereby reverse the direction of rotation of said work holder.

50 55 60 65 7. Apparatus as claimed in claim 3 wherein timing means is provided to interrupt the operation of the apparatus after the completion of a predetermined number of reciprocations of the work holder, said timing means comprising a finger arranged to rotate with said crank, a freely rotatable disc adapted to be turned step-by-step by said finger, a cam surface on said disc, and a switch actuated by said cam surface to interrupt the operation of the apparatus after said disc has been turned through a selected angle.

70 75 8. A method of rounding the leading and trailing edges of an aerofoil sectioned axial flow blade of the kind used in axial flow compressors and turbines, which method comprises inserting the blade lengthwise between a pair of lengthwise running lengths of taut flexible abrading band arranged substantially parallel with their abrading surfaces facing one another and spaced apart by less than the minimum width of the blade, said lengths being

unsupported between their ends, and of a width less than the length of the blade, and then reciprocating the blade substantially lengthwise between said lengths of band and at the same time rotating the blade in opposite directions about its long axis during successive strokes of its reciprocating movement.

9. A method of rounding the leading and trailing edges of an aerofoil sectioned axial flow blade of the kind used in axial flow compressors and turbines, which method comprises inserting the blade lengthwise between a pair of lengthwise portions of a taut flexible endless abrading band arranged substantially parallel with their abrading surfaces facing one another and spaced apart by less than the minimum width of the blade, said lengthwise portions being unsupported between their ends, and the width of the band being less than the length of the blade, and then driving the band to move the band across the leading and trailing edges of the blade while at the same time reciprocating the blade substantially lengthwise and rotating the blade in opposite directions during successive strokes of its reciprocating movement.

10. Apparatus for rounding the leading and trailing edges of an aerofoil sectioned axial flow blade of the kind used in axial flow compressors and turbines, said apparatus comprising a base, a system of pulleys carried from said base, an endless abrading band of a width less than the length of a blade the leading and trailing edges of which are to be rounded, said band having an abrading surface and being supported by said pulley system with each of a pair of lengthwise portions of the band drawn taut between a pair of pulleys of said pulley system, said

5
10
15
20

lengthwise portions being arranged substantially parallel with their abrading surfaces facing one another and spaced apart by less than the minimum width of said blade, means for rotating a pulley of said pulley system to drive said endless band, a support means carried by said base, a work holder carried by said support means, means for rotating said work holder about an axis which passes between said lengthwise portions of the band, said work holder being adapted to support a blade, the leading and trailing edges of which are to be rounded, between said lengthwise portions of the band and lengthwise along said axis of rotation with the leading and trailing edges of the blade lying one on each side of said axis of rotation, means for moving said support means bodily to move said work holder repeatedly towards and away from said lengthwise portions of the endless band thereby to reciprocate a blade carried in said work holder substantially in the direction of its length, and reversing means for reversing the direction of rotation of said work holder each time its direction of bodily movement is reversed.
